UNITED STATES PATENT OFFICE.

CLARENCE P. LANDRETH, OF QUINCY, MASSACHUSETTS.

PROCESS OF MANUFACTURING BELTING.

SPECIFICATION forming part of Letters Patent No. 678,575, dated July 16, 1901.

Application filed November 1, 1900. Serial No. 35,072. (No specimens.)

To all whom it may concern:

Be it known that I, CLARENCE P. LANDRETH, a citizen of the United States, and a resident of Quincy, county of Norfolk, and 5 State of Massachusetts, have invented an Improvement in Processes of Manufacturing Belting, of which the following description, in connection with the accompanying drawings, is a specification, like letters on the drawings representing like parts.

In the manufacture of canvas belts a strip of canvas of suitable width is folded longitudinally one or more times to make a belt of the required width and thickness, and the 15 folds are stitched together so as to preserve the shape of the belt, the lines of stitching generally running parallel and longitudinally of the belt and being a quarter of an inch or thereabout apart. When thus folded and 20 stitched, the belt is passed through a bath of some suitable compound, such as oil, with which the fabric becomes thoroughly saturated, and when in this condition the belt is passed between suitable presser-rolls, which 25 operate to condense the belt and to embed the stitches in the fabric as far as possible. The belt is then passed through a suitable vat containing paint or other similar material, which coats the surface thereof, and is 30 then generally placed upon a suitable stretching-machine, where tension is applied thereto to stretch it, the belt becoming dry while it is being stretched.

Heretofore the process of manufacturing 35 canvas belts has stopped with the drying and stretching of the belt, and the belt after it has been thus treated is placed upon the market and sold.

Canvas belts as heretofore made, generally 40 by a process similar to that outlined above, have several disadvantages which it is the object of my present invention to overcome.

In the first place it has been impossible to 45 completely embed the stitches in the body of the fabric by passing them through the presser-rolls, as aforesaid, because the stitches in any line of stitches occur on each surface of the fabric directly opposite each other and 50 make at that point an increased thickness of fabric which must be compressed to the same thickness as the fabric between the stitches

and must remain thus compressed if the stitches are to remain embedded in the fabric. This, however, has heretofore been impossible of accomplishment, for as soon as the belting leaves the presser-rolls the elasticity of the material expands it at the places where the stitches occur, and the stitches thus protrude somewhat beyond the surface of the 60 fabric, in which condition the belt dries and becomes set. When, therefore, a belt in this condition is first used, the belt contacts with the driving and driven pulleys only on the projecting stitches, with the result that the 65 body of the belt does not rest upon the pulleys, and hence the driving is entirely done by the adhesion between the stitches and the pulleys. This is obviously very much less than would be the adhesion between the entire face of the belt and the pulleys, so that when a belt such as above described is first used its efficiency is below what it should be. Further, the entire wear of the belt comes on 70 the stitches alone, so that the said stitches are frequently worn through before the body of the belt is subjected to much if any wear.

Another disadvantage experienced in the use of canvas belting is that even though the belt is usually put on a stretching-machine 80 to take the stretch out of it, yet when the belt is put in use it stretches after a short time to such an extent as to require shortening in order to be sufficiently tight to drive the machinery.

It is the object of this invention to treat the belt before it is put into use, so that the stitches on the driving-face thereof will be substantially embedded in the body of the fabric and will be thus retained, whereby the 90 driving-face of the belt is perfectly smooth, so that the wear will come evenly on its entire surface, and, further, to bring some of the compound with which the belt has been treated to its surface and iron the same, if 95 desired, thus making a still more smooth and efficient driving-surface. I also heat the belt and stretch the same a second time when hot, thus putting the belt before it is used in the same condition in which an ordinary belt 100 would be after it has been used for some time, whereby when it is first used it does not stretch and has a driving-face of maximum efficiency.

In the drawings accompanying this application I have illustrated diagrammatically an apparatus or a series of devices which may be employed, if desired, in carrying out the steps of my process, although I wish it distinctly understood that the particular form of apparatus described is not essential to my process, as other forms may be used, the form illustrated being chosen to better illustrate my process.

Figure 1 shows diagrammatically an apparatus capable of being used in carrying out my process. Fig. 2 is a detail of said apparatus. Fig. 3 shows a transverse section through a belt before the same has been subjected to my process. Fig. 4 shows a longitudinal section of the same. Fig. 5 shows a transverse section through a belt after having been treated by my process, and Fig. 6 shows a longitudinal section thereof.

In the drawings I have for convenience illustrated what is called a "four-ply" belt; but obviously my process herein to be described is not limited to any particular kind of belt.

In carrying out my process I take a length of canvas belting which has previously been made by the process above outlined—that is, by folding the strip of canvas longitudinally to make a belt of the required width and thickness, sewing the folds together by lines of stitching running longitudinally of the belt, the stitches appearing on and protruding beyond both faces or sides of the belt, as seen at 3 and 5 in Figs. 3 and 4, saturating the belt in a suitable compound, passing it through presser-rolls to compress the fabric and make it dense, painting it, afterward stretching and drying it, and I bring a portion of the compound with which the belt has been saturated to the surface, preferably by heating the belt evenly. The compound appears on the surface of the belt as a viscous gummy coating, for when the belt dries during its previous treatment the compound with which it has been saturated becomes firm and practically solid, and when heat is applied to the belt or it is otherwise treated to soften the hardened compound and bring a portion thereof to the surface of the belt such compound is of a viscous or gummy nature. This heating or otherwise treating of the belt not only softens the compound in the belt and brings a portion thereof to the surface, as above stated, but also softens the belt and renders it more pliable. While thus hot and while in this soft and pliable condition, the belt is subjected to pressure and the stitches on the face thereof are embedded in the body of the fabric, where they are held by the adhesion of the softened compound, which is of a gummy nature, as stated, until the belt is dry again, when the stitches become permanently set in their embedded condition.

As a general rule, only one face of a belt is ever used for a driving-face, and hence it is not necessary to embed the stitches in both

faces of the fabric. I therefore preferably apply pressure to only the stitches 3 on what is to be the driving-face 4 of the belt and embed the said stitches in the body of the fabric, while the stitches 5 on the opposite face of the belt have no pressure applied thereto. By thus treating the belt the embedding of the stitches 3 serves to push the stitches 5 still farther beyond the face of the fabric, and the fabric at the places where the stitches occur is not depressed to an appreciably greater extent than the fabric between the rows of stitches, as would be the case if pressure were applied to the stitches on both faces of the belting at the same time. Figs. 5 and 6 show the belt after having been thus treated. In the prior treatment of the belt the fabric has been condensed to such an extent that the attempt to completely embed the stitches on both faces of the belt in the body of the fabric is liable to destroy the texture of the fabric at the rows of stitches; but by embedding the stitches 3 on one face of the belt and allowing the stitches 5 on the opposite face to protrude and make room for the stitches 3 the fabric is more uniformly compressed and there is no liability of its texture being destroyed. The stitches on the driving-face when thus embedded are retained in the body of the fabric until the belt becomes cold and set by the gummy compound, as described above. Preferably I embed the stitches in one face only of the fabric by applying a pressure uniformly on said face, whereby the protruding stitches are crowded down into the fabric, and at the same time applying to the opposite face pressure only between the rows of stitches, the absence of pressure on the stitches on said face allowing them to protrude to make room for the embedded stitches. During this compressing of the belt, whereby the stitches on the driving-face thereof are embedded in the fabric, to thereby present a perfectly smooth driving-face without any projections thereon, as seen in Figs. 5 and 6, I may, if desired, iron the said driving-face by suitable means, such ironing taking place, preferably, while the belt is still hot and pliable, this ironing of the driving-face serving to still further smooth the same, thereby increasing the efficiency of the belt. After the driving-face of the belt has thus been rendered smooth and while the belt is still hot I subject the same to tension sufficient to extend the belt to practically the limit of its elasticity, and thereby completely take out all of the stretch therein, the belt being allowed to cool and dry in such stretched condition, so that when it becomes set it is incapable of being further stretched. A canvas belt, therefore, when treated by my process presents a perfectly smooth driving-face 4 having maximum efficiency and will not when first used stretch appreciably, so that it is unnecessary to shorten the belt, as is the case when a belt made by the ordinary process is first used.

In the drawings, which illustrate one way in which the process may be carried out, 6 represents a suitable roll upon which the belting, which has been subjected to the ordinary process of manufacture, is retained, and said belt 7 is passed through any suitable heating-chamber 8, the chamber in this instance being shown as heated by coils 9 of steam-pipes, although, of course, the belt might be heated by any other suitable means. This heating of the belt renders the same soft and pliable and also brings the gummy compound with which the belt has been previously saturated to the surface of the fabric. The belt passes from the heating-chamber in its soft and pliable condition and with the composition at the surface of the fabric through suitable presser-rolls, three rolls 10, 11, and 12 being shown in this instance, though the number of rolls is not essential to the carrying out of the process, which rolls are journaled in a suitable support 13 and are movable toward and from each other by means of the screw 14 in a well-known way, the bearings of the rolls being guided in the slot 15 of the standard 13. As illustrated, the central roll 11 has a smooth surface, while the upper and under rolls 12 and 10 are provided in their peripheries with a series of grooves 16, the said grooves being a distance apart equal to the distance between the rows of stitches on the belt and being of sufficient size to receive the stitches, though this is not essential to the process. With this arrangement of rolls and assuming that the under side of the belt 7 as it leaves the roll 6 is to be the driving-face, the said belt passes under the roll 10, between the rolls 10 and 11, and around the roll 11, as shown, by means of which manner of threading the belt through the rolls the driving-face of the belt will contact with the middle roll 11 and the outside of the belt will contact with the rolls 10 and 12.

As stated above, the grooves 16 in the rolls 10 and 12 are so positioned that they receive the lines of stitches on the outside face of the belt, and by reason of the pressure between the said rolls the stitches on the driving-face of the belt are embedded in the fabric and because of the density of the fabric push the stitches on the outside of the fabric farther beyond the face thereof, the grooves 16 providing room for the said stitches.

When the belt leaves the presser-rolls, it has the appearance illustrated in Figs. 5 and 6—that is, the driving-face is perfectly smooth, with the stitches embedded in the fabric and coming flush with the face thereof, while the stitches on the opposite face of the fabric project considerably beyond the surface.

If desired, I may rotate the smooth roll 11 faster than the rolls 10 and 12, whereby the driving-surface of the belt, besides having the stitches therein completely embedded in the fabric, is also ironed by the friction of the roll 11, thus rubbing the compound which is on the surface of the fabric to make a smooth and more efficient driving-surface.

Either or all of the rolls 10, 11, and 12 may be heated by any suitable means, thereby imparting additional heat to the belt and also serving to assist in the ironing step of the process.

As the belt leaves the presser-rolls it is subjected to longitudinal tension sufficient to take the entire stretch out of it, such tension being given to the belt by means of the tension-rolls 18 19, mounted in a suitable support 20, between which rolls the belt passes, the said rolls revolving at a greater surface speed than the rolls 10 and 12, thus stretching the belt between the point where it leaves the compression-rolls and where it enters the tension-rolls. These tension-rolls will either be smooth-faced rolls or the said rolls may have a series of grooves to accommodate the stitches which have been forced beyond the outside of the belt.

Other stretching means than tension-rolls may be employed, if desired, these rolls merely being illustrated as one convenient stretching apparatus.

After the belt leaves the tension-rolls it may be wound upon any suitable drum 21, the drum preferably rotating at such a speed as to maintain the belt in its stretched condition.

After the belt has become thoroughly cold and dry it is ready for use, it having a perfectly smooth driving-face 4, as seen in Figs. 5 and 6, and being practically incapable of further stretching.

The process herein described is not limited in all particulars to the steps described above, but may be varied without departing from the spirit of my invention, which consists in taking a canvas belt made according to the ordinary methods, heating the same, thereby softening and bringing the composition with which it has been saturated to the surface, permanently embedding the stitches in the body of the fabric, and preferably ironing the driving-face and subsequently stretching the belt while still hot.

Having described my invention, what I claim, and desire to secure by Letters Patent, is—

1. The improved process of manufacturing canvas belting which consists in saturating the belt with some suitable compound, such as oil, heating the same, and rubbing or ironing the surface thereof while it is still hot.

2. The improved process of manufacturing canvas belting which consists in folding strips of canvas longitudinally to form a belt of the required width and thickness, saturating the same with a compound such as oil, stretching the belt lengthwise and drying it, and subsequently bringing some of the composition in the body of the belt to the surface, and smoothing the surface of the belt by ironing it.

3. That improvement in the manufacture of canvas belting made from a strip of canvas folded longitudinally and stitched, which belt has been saturated with a suitable compound and dried, which process consists in

subsequently heating the belt to thereby soften and expand the composition with which the belt is saturated and bring a portion thereof to the surface, and smoothing the driving-surface thereof by rubbing or ironing.

4. The improved process of manufacturing canvas belting which consists in saturating the belt in a compound, drying the same and subsequently heating the belt to soften the compound and render the same less adhesive, a portion thereof coming to the surface of the belt, and while the belt is still hot rubbing and smoothing the surface thereof and stretching the same.

15 5. That improvement in the manufacture of canvas belting made from strips of canvas folded longitudinally and stitched, and which has been saturated with a suitable compound, compressed, and stretched lengthwise, which 20 improvement consists in subsequently heating the belt, and pressing the same and embedding the stitches on the face thereof in the body of the fabric while the belt is still hot.

25 6. That improvement in the manufacture of canvas belting made from strips of canvas folded longitudinally and stitched, which belt has been saturated with a suitable compound, compressed, and stretched lengthwise, which 30 improvement consists in subsequently heating the belt, pressing the same and embedding the stitches on the face thereof in the body of the fabric, and stretching the belt while still hot.

35 7. The process of treating canvas belt, which is made from strips of canvas folded longitudinally and stitched and which has been previously saturated in a suitable compound, which process consists in heating the 40 belt thus treated to thereby bring the compound to the surface of the fabric, embedding the stitches on the driving-face of the belt in the body of the fabric, and forcing the stitches on the opposite side thereof beyond 45 the surface, to thus make room for the embedded stitches and ironing the driving-

face, while the belt is still hot, to secure a smooth driving-surface.

8. The process of treating canvas belt, which is made from strips of canvas folded 50 longitudinally and stitched and which has been previously saturated in a suitable compound, which process consists in heating the belt thus treated to thereby bring the compound to the surface of the fabric, embedding the stitches on the driving-face of the belt in the body of the fabric, and forcing the stitches on the opposite side thereof beyond the surface, to thus make room for the embedded stitches, and ironing the driving- 60 face, to secure a smooth driving-surface, and then stretching the belt while the belt is still hot.

9. The process of treating canvas belt which is made from strips of canvas folded 65 longitudinally and stitched, and which has been saturated in a suitable compound and dried, which consists of softening the compound, embedding the stitches on one face of the belt in the body of the fabric, and forcing the stitches on the opposite face thereof beyond the surface to thus make room for the embedded stitches.

10. The process of treating canvas belting which is made from strips of canvas folded 75 longitudinally and stitched, and which has been saturated in a suitable compound which consists in pressing the driving-face of the belt and embedding the stitches thereon in the body of the fabric, and forcing the stitches 80 on the opposite face of the belt beyond the surface thereof to thus make room for the embedded stitches, whereby a smooth driving-face is produced.

In testimony whereof I have signed my 85 name to this specification in the presence of two subscribing witnesses.

CLARENCE P. LANDRETH.
